UNITED STATES PATENT OFFICE

OSCAR E. GEBAUER, OF SCOTTSBLUFF, NEBRASKA

DESIGN FOR A COMBINATION WRIST COMPACT AND MIRROR

Application filed January 14, 1930. Serial No. 34,128. Term of patent 7 years.

To all whom it may concern:

Be it known that I, OSCAR E. GEBAUER, a citizen of the United States, residing at Scottsbluff, in the county of Scotts Bluff and State of Nebraska, have invented a new, original, and ornamental Design for a Combination Wrist Compact and Mirror, of which the following is a specification, reference being had to the accompanying drawing, forming part thereof.

In the drawings:—

Fig. 2 is an edge view thereof.

Fig. 3 is a perspective view thereof in open position.

I claim:

The ornamental design for a combination wrist compact and mirror as shown.

OSCAR E. GEBAUER.
